UNITED STATES PATENT OFFICE.

ALBERT W. GILMORE, OF CHICAGO, ILLINOIS.

CAR-ROOFING.

SPECIFICATION forming part of Letters Patent No. 293,447, dated February 12, 1884.

Application filed November 1, 1883. (No model.)

To all whom it may concern:

Be it known that I, ALBERT W. GILMORE, of Chicago, county of Cook, and State of Illinois, have invented certain Improvements in 5 Car-Roofing, of which the following is a specification.

My said improvement will be hereinafter fully described with reference to the accompanying drawings, in which—

- 10 Figure 1 represents a vertical transverse section of a car-roof embracing the same in its construction; Fig. 2, a plan of the same, showing some of the outside boards of the roof removed, and a portion of the rest and the ridge-plate G broken away, in order to display the parts underlying them; Fig. 3, a 15 longitudinal section of the roof, taken as indicated by the broken line x x in Fig. 1; and Figs. 4 and 5, detail views.
- 20 In the drawings, B indicates the eave-plates of the roof-frame; B', the carlings; G, the ridge-plate, and F the purlins, all of which may be framed or otherwise fastened together. A are the boards of the side walls, which extend up 25 under the outer ends of the sheet-metal plates E, and C are wooden boards fastened upon the upper ends of the vertical boards, and extending up, also, under the metal plates. D are eave-boards, fastened to the side walls 30 for the outer ends of the deck-boards L to rest upon, and are held out from the walls by a series of stop-blocks, s, so as to leave a drip-space, S, between them and the boards C. The stop-blocks are each provided with 35 grooves on the inner side for the lower edge of the lap of two adjacent plates, as shown in Fig. 1. The ridge-plate is considerably higher than the eave-plates, so as to afford a proper slope each way, and is provided on each side 40 with a horizontal groove, g, for the reception of the upper ends of the metal plates E. A very important feature of my improvement are the said metal plates E, which have their upper ends inserted in the groove g in the ridge-plate, which are merely large enough 45 to receive the plain or uncorrugated portions, except where the corrugated portions come; and there the grooves are provided with cross-grooves, as shown at e', Fig. 5, and are then 50 bent, at the edge of the plate, by pressing their bodies down upon the purlins F, and are thus held against slipping down by the pinching

action of the grooves. In order that these sheets of metal may make water-tight joints with each other, and at the same time be secured against slipping asunder laterally, under strain and twisting action when the car is in use, their side edges are bent into a regular and corresponding series of corrugations, so that the sheets can be used interchangeably; and their edges are lapped, as shown in Fig. 4, so as to have one or two corrugations on each side of the joint. In order that the metal sheets may not be forced apart by any lateral strain—one lapping edge being raised 60 off the other—I have provided the boards J, having blocks i fastened upon their under sides at such intervals that one block, i, shall be held down upon every joint, as shown in Fig. 2. The stop-blocks s are also so arranged that one of them shall be abutted against by the lower end of every sheet E, which will thus be prevented from closing or even obstructing the drip-space S, which is provided for any water that may penetrate through the 75 roof-boards L.

It will be observed that the sheet-metal plates break joints with each other, and are held against both vertical and lateral slipping without the use of either nail or pin, and that 80 their upper surfaces are provided with ample air-spaces between them and the deck-boards, and that no recesses are left upon or about them, for the lodgment of water to make rust or do them any damage.

What I claim as new, and desire to secure by Letters Patent, is—

1. The ridge-plate G, provided with two horizontal grooves, g—one in each side—substantially as and for the purpose described.
2. The sheet-metal covering described, held in position above by the pinching action of the grooves in the ridge-plate, and below by the stop-blocks s, substantially as described.
3. The ridge-plate G, having side grooves, g, provided with cross-grooves e' at proper intervals, corresponding to the ridges and grooves made by the corrugations of the metal sheets E, substantially as described.

A. W. GILMORE.
